RADIO SYMBOL GUIDE

Jack W. Adams, Los Angeles, Calif.

Application January 30, 1948, Serial No. 144,181

Term of patent 7 years

(Cl. D52—1)

To all whom it may concern:

Be it known that I, Jack W. Adams, a citizen of the United States, residing at Los Angeles, in the county of Los Angeles, and State of California, have invented a new, original, and ornamental Design for a Radio Symbol Guide, of which the following is a specification, reference being had to the accompanying drawings, forming a part hereof.

Figure 1 is a plan view of a radio symbol guide showing my new design.

Fig. 2 is an edge view.

Figure 3 is a sectional view taken along the line 3—3 of Figure 1.

I claim:

The ornamental design for a radio symbol guide, as shown.

JACK W. ADAMS.
